UNITED STATES PATENT OFFICE.

GEORGE A. LOUD, OF BOSTON, MASSACHUSETTS, ASSIGNOR, BY MESNE ASSIGNMENTS, TO FRANK R. KEITH AND JOHN E. BARRY, COPARTNERS, BOTH OF BOSTON, MASSACHUSETTS.

INTERNAL-COMBUSTION ENGINE.

Application filed January 31, 1924. Serial No. 689,631.

To all whom it may concern:

Be it known that I, GEORGE A. LLOUD, a citizen of the United States, and a resident of Boston, in the county of Suffolk and 5 State of Massachusetts, have invented a new and useful Improvement in Internal-Combustion Engines, of which the following is a specification.

My invention relates to internal combustion engines and more especially to such engines of the two-stroke cycle type commonly known as two cycle engines.

The object of my invention, generally speaking, is to simplify the construction 15 and increase the efficiency of two cycle engines.

A particular object of my invention is to provide means for controlling the flow of the combustible mixture from its source to 20 one portion of a cylinder and thence to another portion of the same cylinder or to another cylinder without the use of cam actuated valves commonly employed for this purpose, the said means consisting in a balanced slide valve, preferably hollow, which is provided with a plurality of ports arranged to co-operate with ports in a pair of cylinders.

Another object of my invention is to 25 provide means whereby the gaseous mixture may be so thoroughly agitated during its passage from its source to the combustion chamber that practically complete combustion without carbonization may be effected, such means comprising an arrangement of parts whereby said mixture is pre-compressed, then expanded and finally compressed in the combustion chamber for ignition. Various other objects of my invention 30 will appear from the following detailed description of an illustrative embodiment of my invention.

With the foregoing objects in view my invention in its preferred form comprises a 35 pair of cylinders having a hollow valve chamber common thereto, said chamber being provided with three sets of ports communicating with each of the cylinders, viz., a set of intake ports arranged substantially midway between the ends of said chamber, a set of ports near the lower end thereof for receiving from the respective cylinders the gaseous mixture after pre-compression, and a set of ports near its upper end 40 for transferring said mixture to the respec-

tive combustion chambers of said cylinders, and a valve in said chamber arranged to control the flow of the mixture through the upper and lower ports.

My invention further comprises a reciprocating valve, preferably hollow, common to both cylinders, and adapted in its movement in one direction to permit the admission of the mixture to the combustion chamber of one cylinder and in its movement in the opposite direction to the combustion chamber of the other cylinder.

My invention comprises also an arrangement whereby the force of the explosion is neutralized with respect to the said reciprocating valve, the latter being provided with a portion having a reduced external diameter registering with the combustion chamber port during explosion so that the effect of the explosion is exerted equally on all 75 portions of said valve provided with the annular peripheral depression and no injurious effect is produced by said explosion upon the valve or upon the wall of its chamber.

My invention consists also in various novel features of construction and arrangement of parts hereinafter more fully described and particularly pointed out in the appended claims.

In the drawings which accompany and form a part of this specification and illustrate the preferred embodiments of my invention—

Fig. 1 is a central vertical section of 90 a two cylinder engine embodying my invention;

Fig. 2 is a vertical elevation taken on the line 2—2 of Fig. 1;

Figs. 3, 4, 5 and 6 are horizontal sections taken on the lines 3—3, 4—4, 5—5, 6—6, respectively, of Fig. 1;

Fig. 7 is a fragmentary vertical section showing the positions of the pistons and the valve when the latter is approaching 100 the limit of its upward movement;

Fig. 8 is a fragmentary vertical section showing the positions of the pistons and valve when the latter is in its highest position;

Fig. 9 is a fragmentary vertical section showing the positions of the pistons and the valve when the latter is approaching the limit of its downward movement;

Fig. 10 is a fragmentary vertical section 110

showing the positions of the pistons and the valve, when the latter is in its lowest position;

Figs. 11 to 14 are diagrams indicating the positions of the various cranks when the pistons and valve are in the positions shown in Figs. 7 to 10, respectively;

Figs. 15 and 16 are horizontal sections taken on the lines 15—15 and 16—16, respectively, of Fig. 10;

Fig. 17 is a fragmentary vertical section of a modification showing the positions of the pistons and valve when the latter is in its highest position;

Fig. 18 is a fragmentary vertical section of said modification showing the positions of the pistons and valve when the latter is in its lowest position.

In the particular drawings selected for more fully disclosing my invention 20 is one wall of a crank casing, the other wall being omitted for the purpose of simplifying the drawings, and in this connection it will be understood, of course, that while I have shown a two-cylinder engine, my invention is applicable to an engine having two or more pairs of cylinders such as illustrated in Fig. 1, and that the illustration of such an engine would be a mere duplication of the apparatus shown in Fig. 1. It is to be understood also that the principle of my invention may be embodied in a single-cylinder engine, except in the case of the modification shown in Figs. 17 and 18.

35. A pair of cylinders 21, 22 are bolted to the crank casing and are provided with pistons 23, 24, respectively, each provided with a tubular extension 25, 26 to which are articulated at 25', 26' the connecting rods 27, 28 journalled on the cranks 29, 30 of the crank shaft 31 which has its bearings in the casing 20.

A suitable water jacket 32 is provided, said jacket surrounding the cylinders and the valve chamber 33 which is intermediate the two cylinders and common thereto, and in which is arranged to reciprocate a tubular valve 34, the lower end of which is articulated at 34' to the connecting rod 35 journalled on the crank 36 arranged at right angles to the main cranks 29, 30, which, as shown, are 180 degrees apart.

The foregoing elements constitute the only moving parts of my improved engine, and it will be noted that said parts are seven only in number, viz, two cylinders, a slide valve, three connecting rods and a crank shaft.

Each piston divides its cylinder into two portions, the explosion chambers 37, 38 at the upper end and the mixing chambers 39, 40 between the lower face of the pistons and the top 41 of the crank casing which closes the cylinders at the lower ends thereof.

65 The explosion chamber 37 is provided

with a set of ports 42 shown in the present instance as four in number, and the valve chamber 33 has near its upper end a set of ports 42', shown in the present instance as three in number, the ports 42, 42' being connected by an upwardly inclined passage 43 and being staggered or out of alignment with each other. 70

It is through these ports that the gas passes to the combustion chamber from the interior of the valve 34. 75

The lower end of the mixing chamber 39 is provided with a set of ports 44 communicating by the passage 45 with the ports 44' in the valve chamber 33, the said ports 44 being staggered with respect to the ports 44'.

It is through these ports that the gas in the mixing chamber after being pre-compressed passes to the interior of the valve 34.

In like manner the combustion chamber 38 has a set of ports 46 communicating by the downwardly inclined passageway 47 with the ports 46' in the valve chamber and being staggered with respect thereto; and

the mixing chamber 40 has a set of ports 48 communicating by the passage 49 with the ports 48' in the valve chamber, the ports 48 and 48' being out of alignment. Intermediate the ends of the valve chamber an inlet passage 50 is provided for the mixture and communicates with the mixing chamber 39 by the ports 51 in the valve chamber, the passageway 52 and the ports 51' in said mixing chamber, the said ports 50, 51' being staggered. The said passageway 50 communicates with the mixing chamber 40 by way of the ports 53 in the valve chamber passageway 54 and the ports 53' in said mixing chamber, the said ports 53, 53' being staggered.

The cylinders 21, 22 are provided with a plurality of exhaust ports 55, 56 respectively, intermediate their ends, said ports communicating with the chambers 57, 58 and the discharge openings 59, 60. 110

The reciprocating hollow valve 34 is provided with four sets of ports, viz, the ports 61 arranged to register with the ports 42' in the valve casing, the ports 62 arranged to register with the ports 46' in the valve casing, the ports 63 arranged to register with the ports 44' in the valve casing, and the ports 64 arranged to register with the ports 48' in the valve casing, and as shown in Figs. 15 and 16, each member of each set of ports in the valve 34 is staggered with respect to the ports with which it registers in the valve chamber, and as above pointed out, the latter are staggered respectively with respect to the ports with which they communicate in the mixing chambers and combustion chambers,—for example, the three ports 63 in the valve are out of alignment with the three ports 44' in the valve chamber, and said ports 44' are out of alignment with the

ports 44 in the mixing chamber end of the cylinder 21.

By means of this arrangement the passage of the gas under pressure from the mixing chamber to the interior of the valve, and from the interior of the valve to the combustion chamber, causes a violent agitation of the same which results in the practically complete mixing of the hydrocarbon fuel 10 and air. Furthermore the interior of the valve 34 has different diameters at different points forming shoulders against which the mixture strikes during its passage therethrough, thereby assisting in the agitation of the mixture as it is forced from the mixing 15 to the combustion chambers.

The valve is provided with two portions having reduced external diameters thereby forming the annular peripheral depressions 20 65 and 66. The depression 65 located midway between the ports 61 and 62 is in communication with the combustion chambers, respectively, at ignition by way of the ports 42', 46', and therefore the pressure resulting 25 from explosion will be exerted equally on every part of the surface of said depression, and will have therefore no injurious effect on said valve which is perfectly balanced, or on the walls of the valve chamber. The 30 length of the annular depression 65 is as shown slightly less than the distance between the lower wall of the port 42' and the upper wall of the port 46' in order to prevent back firing from one explosion chamber 35 to the other.

The depression 66 is at all times in communication with the intake ports 51, 53 so that at the proper times the mixture may be drawn into the mixing chambers by way of 40 the inlet passage 50, around the outside of the valve 34 by way of said depression and thence through said ports 51, 53.

The cycle and operation are as follows:—

The valvular pistons 23, 24 alternate 45 the compression of the fuel charge in the mixing chambers, and the release of the waste gases in the working portion of the cylinder through the exhaust ports 55, 56, the inlet ports 51', 53' through the walls of 50 said cylinders admitting a supply of gaseous mixture to the upper ends of the mixing chambers 39, 40, respectively, to be partly compressed and mixed therein by the downward movement of the piston, and said gaseous mixture after such precompression being conducted from said mixing chambers to the combustion chambers to be further compressed by the movement of the piston in the opposite direction.

60 The four operations of admission, compression, explosion and exhaust which constitute the working cycle are performed during one revolution.

65 Referring to Figures 1 and 7 showing the positions of the moving parts when the valve

is near its upper limit of movement, a partial vacuum has been created in the mixing chamber 39 by the up-stroke of the piston 23 and as soon as the intake ports 51 are uncovered by said piston, a charge of gas is 70 admitted into said mixing chamber by way of the intake passage 50, the annular depression 66 in the periphery of the valve 34, the ports 51 in the valve chamber 33, the passageway 52 and the ports 51'.

In Figs. 1 and 7, ignition having occurred in combustion chamber 37 of cylinder 21, piston 23 is descending, and as soon as the ports 51' are covered by said piston, the gaseous charge admitted as aforesaid in the 80 mixing chamber 39 will be compressed, the maximum compression occurring of course when said piston is in its lowermost position when the crank 29 is at lower dead center, a few degrees before the position shown 85 in Figs. 9 and 13, and then shortly before said crank arrives at the position shown in Fig. 14, the ports 63 in the valve begin their registration with the ports 44' in the valve chamber so that the charge which has slightly 90 expanded owing to the upward movement of the piston 23 but which is still under high pressure, escapes from the mixing chamber 39 by way of the ports 44, passageway 45, ports 44' and 63 into the interior of said 95 valve 34, and thence into the combustion chamber 37 by way of the ports 61 in said valve, the ports 42' in the valve chamber, the passageway 43 and the ports 42 in said combustion chamber (see Figs. 10 and 16). As 100 the crank 29 continues its counterclockwise rotation the piston 23 continues its ascent and the gaseous mixture admitted as aforesaid to the combustion chamber 37 is compressed, the port 61 moving out of register 105 with the port 42', and such compression continues until the said crank reaches upper dead center, whereupon or shortly before or thereafter, ignition occurs, the annular peripheral depression 65 in the valve 34 forming a part of the combustion chamber during 110 explosion.

Near the end of the explosion or power stroke the exhaust ports 55 are uncovered and the products of combustion escape therethrough and pass out through the chamber 57 and passage 59.

If desired the several ports 63 may be arranged to register with the ports 44', and the ports 61 to register with the ports 42' at 120 or about the time the piston 23 is uncovering the exhaust ports 55, so that a certain amount of pneumatic scavenging may be effected by the incoming charge, and in such case said exhaust ports 55 will be closed by the upstroke of the piston before the fresh charge or any appreciable portion thereof has escaped.

Referring to Figure 9 showing the positions of the moving parts when the valve is 130

near its lower limit of movement, a partial vacuum has been created in the mixing chamber 40 by the up stroke of the piston 24, and as soon as the intake ports 53 are uncovered by said piston, a charge of gas is admitted into said mixing chamber by way of the intake passage 50, the annular depression 66 in the periphery of the valve 34, the ports 53 in the valve chamber 33, the passageway 54 and the ports 53'. In Fig. 9, ignition having occurred in combustion chamber 38 of cylinder 22, piston 24 is descending, and as soon as the ports 53' are covered by said piston, the gaseous charge admitted as aforesaid in the mixing chamber 40 will be compressed, the maximum compression occurring of course when said piston is in its lowermost position when the crank 30 is at lower dead center, a few degrees before the position shown in Figs. 7 and 11, and then shortly before said crank arrives at the position shown in Fig. 12, the ports 64 in the valve begin their registration with the ports 48' in the valve chamber 33 so that the charge which has been slightly expanded owing to the upward movement of the piston 24 but which is still under high pressure, escapes from the mixing chamber 40 by way of the ports 48, passageway 49, ports 48' and 64 into the interior of said valve 34, and thence into the combustion chamber 38 by way of the ports 62 in said valve, the ports 46' in the valve chamber, the passageway 47 and the ports 46 in said combustion chamber (see Fig. 8).

As the crank 30 continues its counter-clockwise rotation, the piston 24 continues its ascent and the gaseous mixture admitted as aforesaid to the combustion chamber 38 is compressed, the port 62 moving out of register with the port 46', and such compression continues until the crank reaches upper dead center, whereupon or shortly before or thereafter, ignition occurs, the annular peripheral depression 65 in the valve 34 forming a part of the combustion chamber during explosion.

Near the end of the explosion or power stroke the exhaust ports 56 are uncovered and the products of combustion escape therethrough and pass out through the chamber 58 and passage 60.

If desired the several ports 64 may be arranged to register with the ports 48', and the ports 62 to register with the ports 46' at or about the time the piston 24 is uncovering the exhaust ports 56, so that a certain amount of pneumatic scavenging may be effected by the incoming charge, and in such case said exhaust ports 56 will be closed by the up stroke of the piston before the fresh charge or any appreciable portion thereof has escaped.

In the modification shown in Figs. 17 and 18, the gas after pre-compression in a mix-

ing chamber instead of being transferred to the combustion chamber of the same cylinder is transferred to the combustion chamber of the other cylinder by means of the simple expedient of shifting the positions of the ports 63, 64 to the right and left, respectively, as shown at 63', 64' in Figs. 17 and 18, although, as will be obvious this result may be effected by other means.

The cycle and operation of the engine shown in Figs. 17 and 18 is as follows:

A charge of gas is drawn into the mixing chamber 39 near the end of the up stroke of the piston 23 in the manner already explained, and simultaneously with this operation a charge of gas is compressed in the combustion chamber 37 and is ignited therein, whereupon said piston descends, and upon its arrival at a position slightly above that shown in Fig. 17, the valve 34 moving upwardly brings its port 64' into registration with the port 44' and its port 62 into registration with the port 46'. The piston 23 continuing its power stroke forces the mixture precompressed in the mixing chamber 39 through the ports 44, passage 45 and ports 44' and 64' into the interior of the valve 34 and then through the port 62 in said valve, the port 46' in the valve chamber, the passage 47, and the port 46 in the combustion chamber 38 of the cylinder 22, in which combustion chamber said mixture is compressed by the up stroke of the piston 24 as soon as the port 46' is closed by the downward movement of the valve.

A charge of gas is drawn into the mixing chamber 40 near the end of the up stroke of the piston 24 in the manner already explained, and simultaneously with this operation a charge of gas is compressed in the combustion chamber 38 and is ignited therein, whereupon said piston descends, and upon its arrival at a position slightly above that shown in Fig. 18, the valve 34 moving downwardly brings its port 63' into registration with the port 48' and its port 61 into registration with the port 42'. The piston 24 continuing its power stroke forces the mixture precompressed in the mixing chamber 40 through the ports 48, passage 49 and ports 48' and 63' into the interior of the valve 34 and then through the port 61 in said valve, the port 42' in the valve chamber, the passage 43 and port 42 in the combustion chamber 37 of the cylinder 21, in which combustion chamber said mixture is recompressed by the up stroke of the piston 23 as soon as the port 42' is closed by the upward movement of the valve.

Having thus described illustrative embodiments of my invention without however limiting the same thereto, what I claim and desire to secure by Letters Patent is:

1. An internal combustion engine comprising in combination, a cylinder, a piston

- reciprocating therein and dividing said cylinder into a mixing and an explosion chamber, a crank shaft operated by said piston, a valve chamber, a tubular valve in said chamber co-operating with the gas feed and formed with an exterior annular recess to register with the feed ports of the mixing chamber and a second annular recess as a part of the explosion chamber thereby to balance said valve at time of explosion, the bore of said valve being adapted to intercommunicate with the mixing and explosion chambers, and means for igniting the gas charge in said explosion chamber.

2. An internal combustion engine comprising in combination, a cylinder, a piston reciprocating therein and dividing said cylinder into a mixing and an explosion chamber, a crank shaft operated by said piston, a valve chamber, a tubular valve in said chamber co-operating with the gas feed and formed with an exterior annular recess to register with the feed ports of the mixing chamber and a second annular recess as a part of the explosion chamber thereby to balance said valve at time of explosion, the bore of said valve being interrupted and adapted to intercommunicate with the mixing and explosion chambers, and means for igniting the gas charge in said explosion chamber.

3. An internal combustion engine comprising in combination, a power shaft, a pair of co-operating cylinders, valvular pistons therefor which divide the cylinders to create in each a mixing chamber and an explosion chamber, said pistons being adapted to open the feed ports for inflow of gas to the mixing chambers upon completion of the compression stroke and to release the exhaust gases from the explosion chambers on the mixing stroke, a tubular valve connecting with a gas supply common to said cylinders and equipped with a plurality of ports interconnecting the said mixing and explosion chambers on the mixing stroke, a tubular valve connecting with a gas supply common to said cylinders and equipped with a plurality of ports interconnecting the said mixing and explosion chambers of the same cylinder, the ports on one side of said valve being out of alignment with those on the opposite side thereof, co-operating mechanism to actuate the valve and move said ports in unison to permit the gas to pass through the bore of the valve, first from the mixing chamber of one cylinder to the explosion chamber of the same cylinder and then from the mixing chamber of the other cylinder to its explosion chamber, and means for igniting the gas charge in the explosion chamber.

4. An internal combustion engine comprising in combination, a cylinder having a set of ports, a valve chamber having a set of ports communicating with the ports in said cylinder, each port of one set being staggered with respect to the ports of the other set, and a valve in said valve chamber for controlling the ports therein.

5. An internal combustion engine comprising in combination, a cylinder having a set of ports, a valve chamber having a set of ports communicating with the ports in said cylinder, each port of one set being staggered with respect to the ports of the other set, and a hollow valve in said valve chamber for controlling the ports therein, said hollow valve having a set of ports, each member of which is staggered with respect to the ports of the other two sets.

In testimony whereof, I have hereunto subscribed my name this 17th day of December, 1923.
